RAZOR HONING DEVICE

Vincent Munno, Hoboken, N. J.

Application April 12, 1946, Serial No. 661,778

3 Claims. (Cl. 51—214)

1

This invention relates in general to a honing device and in particular to a honing device for sharpening precision tools such as razors, scalpels and the like.

This invention contemplates a precision honing device for refinishing exceptionally sharp and even cutting edges on razors, surgical instruments and the like wherein it is necessary to have particularly sharp and smooth cutting edges. Accordingly it is an object of this invention to provide a precision honing device.

It is another object of this invention to provide a precision honing device having a plurality of rotating members adapted to receive and sharpen a precision cutting tool.

It is a further object of this invention to provide a precision honing device comprising a support having a pair of rotatably mounted spherical members positioned to bear against one another and to receive and sharpen a precision cutting tool.

Additional objects of this invention as well as its use, construction and operation will in part be obvious and will in part become apparent from the following disclosure.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of a precision honing device according to one form of this invention.

Fig. 2 is an end cross section of the articles shown in Fig. 1, taken along the line 2—2.

Fig. 3 is a side elevational view of the article shown in Figs. 1 and 2.

Fig. 4 is a perspective view of a precision honing device according to a somewhat different form of this invention wherein the device is removably mounted on a work bench or the like.

Fig. 5 is a perspective view of a still further form of the invention removably mounted on a work bench or the like.

Fig. 6 is a plan view of a blank which is adapted to be shaped to form the article shown in Fig. 5.

Fig. 7 is a perspective view of an adjustable precision honing device according to a still further form of this invention.

Fig. 8 is an end cross section of the device shown in Fig. 7, taken along the line 8—8.

Fig. 9 is an enlarged fragmentary cross section

of the adjustable means in the device according to Figs. 7 and 8.

Referring to the figures in detail there is shown in Figs. 1-3, a precision honing device generally designated 10 comprising a stem or mounting member 11 having a clamp-like frame 12 positioned thereon. A pair of spherical sharpening members 13 are rotatably mounted in clamp 12 and are positioned to bear against one another.

10 The stem 11 is a suitable and convenient handle or mounting member adapted to fit, according to the particular needs, into a conventional mounting clamp or the like, or alternatively adapted to be held in an operator's hand. This stem may be constructed of wood, metal, plastic or other similar relatively stiff and sturdy structural materials.

15 The clamp or frame 12 comprises a base 14 which is secured to stem 11 and which has two side or arm members 15 rising from the sides thereof and facing one another. Near the top or free end of arm 15 are two holes or recesses 16, one hole in each of arm members 15. These holes 16 are positioned directly opposite one another and are adapted to receive spherical members 13.

20 Spherical members 13 comprise relatively hard and precision formed balls having a diameter substantially larger than the diameter of holes 16. These spherical members 13 are positioned in holes 16 and on the inner sides of arms 15 whereby members 13 bear against one another. These members are loosely positioned in holes 16 and therefore are adapted to rotate therein.

25 Clamp 12 is constructed of a strong and resilient material, such as spring steel or the like whereby it is adapted to retain spherical members 13 firmly yet springably in position.

30 Spherical members 13 are constructed of a hardened steel or similar hard material, and are substantially harder than the adjacent arm members 15, as well as being substantially harder than conventional cutting members such as razor blades and the like. These spherical members 13 are accurately formed to a nearly perfect spherical shape, substantially free from irregularities and defects.

35 In use and operation the device shown in Figs. 1-3 is firmly grasped in the operator's hand or alternatively, and preferably, is securely fastened to a work bench or the like, and the instrument to be sharpened is carefully and slowly passed through the honing device, placing the sharp cutting edge between spherical members 13. The cutting edge is passed between spherical members 13 once or several times until the edge is thoroughly and satisfactorily sharpened.

In Fig. 4, there is shown a somewhat different form of this invention, wherein stem 11 is omitted from the structure. In this form of the invention, a honing device comprising a clamp 12 having parallel placing arms 15 in which are mounted spherical members 13 in a structure similar to that described in Figs. 1-3. The bottom of clamp 12 is substantially flat whereby it is adapted to be positioned directly on a flat surface.

There is likewise provided an adjustable clamp 17 preferably a C clamp or the like. One arm 18 of this clamp is adapted to be positioned above the base 14 of member 12 and the other arm 19 of clamp 17 is adapted to be positioned below a work table 20 or other similar surface. Thumb screw 21 or the like serves to releasably secure the honing device to the upper surface of table 20, as shown in Fig. 4.

The use and operation of this form of the device is similar to that previously described, with the honing device being mounted on the upper surface of a work table and a precision cutting tool being sharpened thereon as previously described.

In Figs. 5 and 6, there is shown a somewhat different form of the invention wherein clamp 17, according to Fig. 4, is formed as an integral part of the honing device 10. In this form of the invention the honing device comprises blank 22 of spring steel, as shown in Fig. 6, in the form of a T having two holes or recesses 16 near opposite ends of the cross bar of the T and having a small threaded hole 23 near the face or stem of the T.

The blank is opened along dotted lines, as shown in the figure, with arms 15 of the cross bar being bent upwardly at right angles and with stem 24 of the T being bent downwardly at right angles. The bottom portion 25 of the stem 24, containing hole 23 is further bent backwards at right angles whereby it is positioned directly beneath and parallel with the central or crossing portion 14 of the T. The finished formation is shown in Fig. 5.

The thumb screw 21^a or the like is passed through threaded hole 23 whereby there is formed an adjustable clamp for securing the device to a work table or the like. A pair of spherical members 13 are positioned between arms 15, resting in holes 16 therein in a structure similar to that shown in connection with the previous figures. The use and operation of this device is similar to that previously described.

In Figs. 7-9, there is shown a still further form of this invention wherein the tension acting on spherical members 13 is adjustable. The structure is similar to that shown in the previous figures, in particular the structure shown in Figs. 1-3, with the exception that a tension adjusting means 27 is mounted between arms 15^c at a point substantially half way between spherical members 13^c and base 14^c of the device.

According to this form of the invention, this adjusting means 27 comprises bolt 28 having a right handed thread thereon mounted in one arm 15^c and a bolt 29 having a left handed thread thereon mounted in the other arm 15^c (see Fig. 9) and a knurled ring or collar 30 having mating threads for bolts 28 and 29 threadedly and adjustably joining said bolts 28 and 29.

The ends 31 of bolts 28 and 29 are rectangular or irregular in shape, and are adapted to fit into mating recesses in arms 15^c whereby rotation of bolts 28 and 29 with respect to arms 15^c is prevented. Thereby, when collar 30 is rotated the

effective additive length of bolts 28 and 29 is increased or decreased as desired. As the length of bolts 28 and 29 is decreased arms 15^c are allowed to come together whereby the full tension of the clamp 12^c is caused to act on spherical members 13^c. As the effective length of bolts 28 and 29 is increased an accurately adjusted proportion of this tension is removed from spherical members 13^c.

10 The use and operation of this device is similar to that shown in connection with the previous figures with the exception that there is available a fine adjustment of the characteristics of the honing device. For relatively coarse work, the tension of the device is tightened whereby spherical members 13^c are caused to bear relatively firmly against one another. For the final and exceptionally fine sharpening, collar 30 is adjusted to cause spherical members 13^c to bear 15 against one another only lightly whereby an extremely sharp cutting edge may be formed on the tool which is being sharpened.

While I have illustrated and described the preferred embodiments of my invention, it is to be understood that I do not limit myself to the precise constructions herein disclosed and the right is reserved to all changes and modifications coming within the scope of the invention as defined in the appended claims.

30 Having thus described my invention, what I claim as new, and desire to secure by United States Letters Patent is:

1. In a honing device having a U-shaped frame rotatively supporting a pair of balls in contact 35 with each other adjacent the outer free ends of the flexible arms of said frame, means for varying the spacing of said arms to vary the pressure with which the balls engage each other, comprising bolts non-rotatively mounted in axial alignment 40 on the inner faces of said arms and directed toward each other, said bolts having threads of opposite hand, and a tubular collar having said bolts threadedly engaged into its ends, whereby the collar may be turned in one 45 direction to extend the bolts and spread the arms to reduce the pressure on the balls and in the opposite direction to draw the bolts together and relieve the arms to increase the pressure on the balls.

50 2. In a honing device having a U-shaped frame rotatively supporting a pair of balls in contact with each other adjacent the outer free ends of the flexible arms of said frame, means for varying 55 the spacing of said arms to vary the pressure with which the balls engage each other, comprising bolts non-rotatively mounted in axial alignment on the inner faces of said arms and directed toward each other, said bolts having threads of opposite hand, and a tubular collar having said 60 bolts threadedly engaged into its ends, whereby the collar may be turned in one direction to extend the bolts and spread the arms to reduce the pressure on the balls and in the opposite direction to draw the bolts together and relieve the arms to increase the pressure on the balls, said tubular collar having its outer surface knurled to facilitate gripping the same for turning purposes.

65 3. In a honing device having a U-shaped frame 70 rotatively supporting a pair of balls in contact with each other adjacent the outer free ends of the flexible arms of said frame, means for varying the spacing of said arms to vary the pressure with which the balls engage each other, comprising bolts non-rotatively mounted in axial align-

ment on the inner faces of said arms and directed toward each other, said bolts having threads of opposite hand, and a tubular collar having said bolts threadedly engaged into its ends, whereby the collar may be turned in one direction to extend the bolts and spread the arms to reduce the pressure on the balls and in the opposite direction to draw the bolts together and relieve the arms to increase the pressure on the balls, said bolts having their outer ends irregularly shaped and extended into mating recesses formed in the inner faces of said arms preventing rotation of said bolts relative to said arms. 10
